UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

SHEET-FOLDING MACHINE.

1,171,920.

Specification of Letters Patent. Patented Feb. 15, 1916.

Application filed March 4, 1914. Serial No. 822,433.

To all whom it may concern:

Be it known that I, HOWARD M. BARBER, a citizen of the United States, and resident of Stonington, in the county of New London 5 and State of Connecticut, have invented a new and useful Improvement in Sheet-Folding Machines, of which the following is a specification.

This invention relates to that type of 10 sheet folding machines in which the sheets are perforated along the line of fold so as to release the air as the sheets are folded for preventing them from bulging, thereby permitting them to be folded flat.

15 The object of this invention is to provide novel means for accomplishing the above result, such means including the employment of a folding blade also as a perforating blade, both the perforating and the folding 20 operations being accomplished while the sheets are on their carrier, thereby insuring perfect register for the sheets during these operations.

A practical embodiment of the invention 25 is represented in the accompanying drawings in which,

Figure 1 illustrates in side elevation so 30 much of a sheet folding machine as will give a clear idea of the invention. Fig. 2 is a diagrammatic section illustrating the parts for passing the sheets through the machine. Fig. 3 is a section taken just inside the side frame. Fig. 4 is an end view of the combined perforating and folding blade, and 35 Fig. 5 is a plan view of the same.

The rotary sheet carrier 1 is herein shown as a cylinder and as provided with three sets 40 of grippers 2, and three combined sheet perforating and folding blades 3. The web is fed to the rotary cylinder 1, through the pair of coacting rotary cutters 4 and 5 and guides 6, 7. The combined sheet perforating and folding blades 3 coat with the yielding 45 nad 8 in the rotary carrier 9, for perforating the sheets along the line of fold. These blades 3 also coat with a set of folding devices 10, in the present instance, floating 50 folding jaws, carried by a rotary carrier 11. The first folded sheets are transferred from the folding devices 10, to the grippers 12, of a rotary carrier 13, in the present instance a cylinder, upon which cylinder the sheets 55 may be slit lengthwise of their travel by the slitter 14. Each section of the first folded

60 sheets may be creased lengthwise of its travel, by the creaser 15, along the line of its next fold. The sheets are then transferred from the cylinder 13 to the folding table 16, through the rotary sheet carrier 17 and its grippers 18.

65 The cylinder 1 is arranged to collect two sheets on each of its three surfaces, the first sheet of each section being held in register on its respective surface by the friction pulleys 19, while the grippers 2 are opened to receive the second sheet. The grippers 2 on the collecting cylinder are opened to receive a sheet every revolution of the cylinder, by the stationary cam 20. These grippers are opened every second revolution for folding 70 off a collected group of two sheets to the rotary carrier 11, by a movable cam 21, operated by a suitable cam 22 on the shaft 23 of the rotary carrier 9.

75 The floating folding jaws 10 on the rotary sheet carrier 11, are floated in parallelism with their coacting combined perforating and folding blade 3, at the time of the folding operation and are moved into a position substantially tangent to the surface of 80 the slitting and creasing cylinder 13, at the time of transferring the first folded sheets to the grippers 12. The usual cam for floating these jaws 10, is denoted by 24, and the cams for opening the jaws at the proper 85 times are denoted by 25, 26. The cams for opening the grippers 12 on the slitting and creasing cylinder 13, for receiving the sheets from the folding jaws 10 and transferring them to the grippers 18 on the rotary sheet 90 carrier 17, are denoted by 27, 28, respectively. The cam for opening the grippers 18 to receive the sheets from the slitting cylinder 13 and transfer the same on to the folding table 16, is denoted by 29. It is 95 to be understood that suitable tape carriers 30, 31, are provided for feeding the sheets on to the said table 16.

A train of gears 32, 33, 34, connect the rotary cutters 4, 5, with the cylinder 1. A 100 train of gears 35, 36, 37, connect the rotary cutters with the web feed roll 38. The friction pulleys 19 are driven from the gear 34, through the gear 39, and the rotary gear 9 is also driven from the gear 34, through the 105 gear 40. The rotary sheet carriers 11, 13 and 17 are driven from the gear 34, through the gears 41, 42, 43. The slitter 14 is driven

from the gear 42, through the gear 44, and the creasers 15 are driven from the gear 42, through the gear 45.

In operation, the web is fed by the roll 38, down between the rotary cutters 4, 5, and guides 6, 7, to the collecting cylinder 1. This cylinder is arranged to collect a product of two sheets on each of its three surfaces. Just after the two sheets have been 10 collected, on each surface, the blade 3 for said surface coacts with the yielding block 8 of the rotary carrier 9, for the purpose of perforating the sheets along the line of fold just before the folding operation. This 15 perforating operation is accomplished by providing the blade 3 with a serrated edge 46. The further rotary movement of the cylinder 1 brings the blade 3 into coaction with the folding jaws 10 of the rotary sheet 20 carrier 11, whereby the sheets will have a transverse fold imparted to them as they are folded off on to the rotary sheet carrier 11. The first folded sheets are then transferred 25 from the folding jaws 10 to the grippers 12 on the cylinder 13, where the said sheets may be slit and creased. They are then transferred to the folding table 16, by the grippers 18 of the cylinder 17.

It will be seen that by perforating the 30 sheets on the same carrier from which they are folded off, the sheets may be held in absolute register during the perforating operation. It will also be seen that by utilizing the blades 3 both as perforating 35 and folding blades, the mechanism is materially simplified.

It is evident that various changes may be resorted to in the construction, form and arrangement of the several parts without 40 departing from the spirit and scope of my invention, and hence I do not wish to limit myself strictly to the structure herein set forth, but

What I claim is:

45 1. In a sheet folding machine, a rotary sheet carrier and a device thereon arranged to respectively perforate and fold off the sheet at different points in the travel of the carrier.

50 2. In a sheet folding machine, a rotary sheet collector and a device thereon ar-

ranged to respectively perforate and fold off the collected sheets at different points in the travel of the collector.

3. In a sheet folding machine, folding 55 mechanism including coacting folding devices, one arranged to also perforate the sheet along the line of fold before the folding operation at a point different from its folding-off point.

4. In a sheet folding machine, two rotary sheet carriers having coacting folding devices, the folding device on one carrier also serving to perforate the sheet along the line of fold before the folding operation at a 65 point in the travel of the carrier different from its folding-off point.

5. In a sheet folding machine, folding mechanism including a rotary sheet carrier provided with a combined sheet perforating 70 and tucking blade having a serrated edge.

6. In a sheet folding machine, folding mechanism including a rotary sheet collector provided with a combined sheet perforating and tucking blade having a serrated edge. 75

7. In a sheet folding machine, folding mechanism including a rotary sheet carrier having a combined sheet perforating and tucking blade, a rotary carrier having a surface arranged to coact with the blade for 80 perforating the sheets and a rotary sheet carrier having folding jaws arranged to coact with the said blade for folding sheets along the line of perforations.

8. In a sheet folding machine, folding 85 mechanism including a rotary sheet collector having a combined sheet perforating and tucking blade, a rotary carrier having a surface arranged to coact with the blade for perforating the collected group of sheets, 90 and a rotary sheet carrier having folding jaws arranged to coact with the said blade for folding the group of sheets along the line of perforations.

In testimony, that I claim the foregoing 95 as my invention, I have signed my name in presence of two witnesses, this twenty sixth day of February, 1914.

HOWARD M. BARBER.
